(57) **CLAIM**

The ornamental design for a water supplying machine for endoscope, as shown and described.

DESCRIPTION

FIG. 1 is a perspective view from upper and right side of a water supplying machine for endoscope, showing our new design;

FIG. 2 is a front view thereof;

FIG. 3 is a rear view thereof;

FIG. 4 is a top plan view thereof;

FIG. 5 is a bottom plan view thereof;

FIG. 6 is a right side view thereof;

FIG. 7 is a left side view thereof;

FIG. 8 is a right side view of a water tank of the water supplying machine for endoscope;

FIG. 9 is a cross-sectional view of 9-9 line in FIG. 8 of the water tank;

FIG. 10 is cross-sectional view of 10-10 line in FIG. 8 thereof;

FIG. 11 is a cross-sectional view of 11-11 line in FIG. 8 thereof; and,

FIG. 12 is a cross-sectional view of 12-12 line in FIG. 8 thereof.
